F. A. LESTER.

CAR ROOF.

APPLICATION FILED JULY 30, 1914.

1,218,676.

Patented Mar. 13, 1917.

UNITED STATES PATENT OFFICE.

FREDERICK A. LESTER, OF CHICAGO, ILLINOIS, ASSIGNOR TO CHICAGO STANDARD EQUIPMENT COMPANY, OF CHICAGO, ILLINOIS, A CORPORATION OF MAINE.

CAR-ROOF.

1,218,676.

Specification of Letters Patent. Patented Mar. 13, 1917.

Application filed July 30, 1914. Serial No. 854,029.

To all whom it may concern:

Be it known that I, FREDERICK A. LESTER, a citizen of the United States, residing at Chicago, in the county of Cook and State 5 of Illinois, have invented certain new and useful Improvements in Car-Roofs, of which the following is a specification, reference being had to the drawings forming a part hereof.

10 My invention relates generally to roofs, and has reference more particularly to the provision of an improved outside roof peculiarly adapted for use in connection with railway freight cars; and has for one of its 15 main objects to produce a water-tight roofing which may be readily applied to the car and at minimum cost.

Another object is to so conform and arrange the members composing the roof that 20 the roofing board strips are free to expand and contract within the headed battens, and to so utilize the expansion of the roof as to effect a tightening of the head of the batten on the boards at a time when it is most 25 desirable and necessary to prevent leakage past the joint. A still further object is to provide a metallic headed batten having separated flanges interposed between adjacent boards and adapted to be brought together or collapsed by the expansion or 30 swelling of the boards in order to additionally tighten the joint between the boards and the head of the batten.

These, together with such other objects 35 as may hereinafter appear, or are incident to my invention, I attain by means of a construction illustrated in preferred form in the accompanying drawings, wherein:—

Figure 1 is a perspective view of a portion 40 of a car showing the application of my invention thereto.

Fig. 2 is a section taken through the roof on the line II—II of Fig. 1.

Fig. 3 is a similar view when the boards 45 have expanded against the battens.

Fig. 4 represents a side elevation of the batten, illustrating the manner of its fastening to one of the boards.

Fig. 5 is an enlarged perspective of a 50 fragmentary portion of the batten.

Referring to the drawings, the numeral 6 indicates the carlines extending transversely across the roof between the car sidings 7, the former carrying the purlins or nailing 55 strips 8 to which the outer roof covering,

embodying my invention, is adapted to be attached. This covering comprises the roofing boards or strips 9 set out at intervals to receive therebetween the metallic battens 10 which unite the side edges of the boards and comprise the joining members of the group. Each strip may be formed with the side channels 9^a, and is secured to the purlins preferably at or near one marginal side edge thereof by fastening elements 11, so as to leave the opposing side edge of the strip free to expand or contract relatively of the secured edge.

Each of the battens 10 may be formed from a thin metal blank to embody a hollow head having inturned and normally separated portions 10^a and 10^b, from which latter depend the spaced flanges 12^a and 12^b; the portions 10^a and 10^b bearing laterally upon the secured and free side edges respectively of adjacent strips and the flanges being interposed in their spaced relation between them. These flanges are preferably divergent, as in the manner shown, to provide at or near their lower terminals a means for normally gaging the proper distance between the strips, and are fastened at extended intervals to the secured edge of the strip by nails 13 which may pass through both of the flanges, as indicated in Fig. 4. 85

Under ordinary weather conditions the normal relation of members at the joint is illustrated in Fig. 2, the free edge of the strip being capable of moving under the portion 10^b to collapse the flanges, as in Fig. 3, when the strip swells and expands during wet weather. As the flanges collapse the side margins 12 of the head are drawn inwardly and downwardly to pinch the adjacent edges of both strips at or near the channels 9^a, thus tightly sealing the joint at a time when a tight joint is absolutely necessary to prevent leakage into the car.

By having the flanges divergent, the full force of the tightening or pinching effect of the head on the free edge of the strip is not immediately felt, but is at first gradual so as not to materially hinder the full movement of the edge to, or near, the position taken up in Fig. 3. When in this position, those portions of the head not drawn in to more tightly engage with the strips are slightly humped or curved as indicated at 10^x, which is due to the collapsed flanges 12^a and 12^b acting to inwardly contract the 110

lower portions 10^a and 10^b against the resistance offered by the top portion of the head. In practice, it is also found that the upper portions of the flanges penetrate slightly 5 into the hollow of the head, and in this way tend to add to the pinching effect of the side portions 12.

It will be obvious from the above description that while expansion of the strips is 10 readily permitted, yet at the same time an absolutely tight joint is provided when most needed. Furthermore, as the strip contracts 15 the pressure on its free edge correspondingly lessens so as to permit its return to normal position. From the foregoing, the 20 essential features and elements of the construction, together with its simplicity and other advantages thereof will be readily apparent to those skilled in the art.

I do not intend to restrict myself to the precise details of construction as shown, for 25 it is deemed obvious that modifications thereof may be made without departing in any way from the spirit and scope of the invention as pointed out in the appended claims.

Having thus described and illustrated its use, what I claim as new and desire to secure by Letters Patent, is the following:—

1. A metallic roof batten formed of relatively thin flexible metal and comprising a roof strip engaging head provided with dependent flared flanges adapted to lie between

adjacent roof strips, said portions serving when sprung toward each other by the expansion of the roof to tighten the engagement of the head with the roof strips. 35

2. A metallic roof batten formed of relatively thin flexible metal and comprising a hollow roof strip engaging head provided with dependent flared spaced flanges adapted to lie between adjacent roof strips, said portions serving when sprung toward each other by the expansion of the roof to tighten 40 the engagement of the head with the roof strips. 45

3. In a car roof, the combination of spaced roofing strips, a metallic batten for uniting the side edges of said strips and secured to one of the strips, said batten formed of relatively thin flexible metal and comprising a hollow strip engaging head having dependent spaced flanges adapted to lie between adjacent roof strips, said flanges constructed and arranged when sprung toward each other by the expansion 50 of the roof to tighten the engagement of the head with the roof strips, substantially as described. 55

In testimony whereof I have hereunto signed my name in the presence of the two subscribing witnesses.

FREDERICK A. LESTER.
